UNITED STATES PATENT OFFICE.

BENJAMIN F. PIERCE, OF PINE BLUFF, NORTH CAROLINA.

DESIGN FOR A PINCUSHION.

Application filed February 3, 1923. Serial No. 5,071. Term of patent 3½ years.

To all whom it may concern:

Be it known that I, BENJAMIN F. PIERCE, a citizen of the United States of America, residing at Pine Bluff, in the county of Moore and State of North Carolina, United States of America, have invented a new, original, and ornamental Design for Pincushion, of which the following is a specification, reference being had to the accompanying drawings, forming a part hereof.

The figure is a perspective view showing my new design.

I claim:

The ornamental design for a pincushion as shown.

BENJAMIN F. PIERCE.

Witnesses:

Mrs. ZOE HOWARD,
MARGARET A. KITTELL.
